The border of this part of the label is quadrangular with ornamental corners a, a and b, b, and with ornaments c, c at the middle of each side and ornaments d, d at the middle of the top and bottom.~~

On that part of the label shown in fig. 2 are the royal arms of England occupying the centre, with the words "Established 1776 Old English Mustard Co" above and the words "Durham Mustard G. J. & C. Le Blond and Co London" below, the whole surrounded by a plain border with ornamental corners. The word "Established" and the numeral "1776" are in one straight line at the top, the word in small antique Roman letters with a capital initial, and the date "1776" in antique Straboc numerals. The words "Old English Mustard Co" are in shaded old English letters with the initials only in capitals, the words "Old English" in one straight line below "Established 1776", and the words "Mustard Co" in a curved line over the royal arms. The word "Durham" is in shaded Roman capitals, arranged in a curved line under the royal arms, and the word "Mustard" in shaded fancy block letters.

Le Blond & Co." are in small plain block letters, arranged in a straight line in the lower left hand corner, and the words "London" in similar letters arranged in a straight line in the lower right hand corner. On each of those portions of the label, one of which is represented in fig. 3, is a perspective view of a factory and sheds, occupying the centre, within a circular border *g.* with the words "Old English Mustard Co. above, and the words "J. J. & C. Le Blond & Co. London, Established, 1776," below, the whole surrounded by a plain border with ornamental corners. The words "Old English Mustard" bear in shaded Roman letters the initials only in capital letters, the words "Old English" in one curved line above the words "Mustard Co." in another curved line. The words "J. J. & C. Le Blond & Co." are in shaded Roman capitals with larger initials arranged in a curved line below the central view, and above the word "London" which is in shaded Roman capitals in another curved line. The word "Established" and the date "1776" are in letters and numerals similar to those at the top of fig. 3 and are arranged in a straight line at the bottom of the label.

The border of this part of the label is of quadrangular form and intertwined at the middle of its sides with the circular border *g.* before mentioned, but otherwise it is plain, with the exception of the four similar ornaments *h.* at its corners.
